CLAIM

The ornamental design for a wall-mounted hook plate, shown and described.

DESCRIPTION

FIG. 1 is a front, top and right side perspective view of a wall-mounted hook plate showing my new design;

FIG. 2 is a right side elevational view thereof, the side opposite being a mirror image;

FIG. 3 is a front elevational view thereof;

FIGS. 4 and 5 are respectively top and bottom plan views;

FIG. 6 is a rear elevational view thereof; and,

FIG. 7 is a front, top and right side perspective view of a second embodiment thereof, the rear elevational view thereof being plain and unadorned.

FIG. 1

FIG. 2

FIG. 3

FIG. 4

FIG. 5

FIG. 6

FIG. 7
